UNITED STATES PATENT OFFICE

149,193

DESIGN FOR A WHEELED VEHICLE OR
SIMILAR ARTICLE

Edward Larralde, La Canada, Calif., assignor to
A. C. Mfg. Co., Van Nuys, Calif., a corporation
of California

Application January 13, 1947, Serial No. 136,127

Term of patent 3½ years

(Cl. D14—3)

To all whom it may concern:

Be it known that I, Edward Larralde, a citizen of the United States, residing at La Canada, in the county of Los Angeles and State of California, have invented a new, original, and ornamental Design for Wheeled Vehicle or Similar Article, of which the following is a specification, reference being had to the accompanying drawing, forming part thereof.

Referring to the drawing:

Figure 1 is a perspective view of the front and one side of a wheeled vehicle, showing my new design.

Figure 2 is a view in side elevation of the wheeled vehicle of Figure 1.

Figure 3 is a view in front elevation of the wheeled vehicle of Figures 1 and 2.

I claim:

The ornamental design for a wheeled vehicle or similar article, substantially as shown.

EDWARD LARRALDE.
